MAXWELL MCGUINNESS, OF LONDON, ENGLAND

AGITATING AND CONVEYING APPARATUS

Application filed January 29, 1929, Serial No. 335,987, and in Great Britain February 11, 1928.

This invention relates to the treating of materials particularly by mechanical agitation during conveyance with or without simultaneous chemical or physical treatment such as by heat. The apparatus embodying the present invention is particularly applicable to the treatment of materials that become tacky or plastic when heated such for example as shale coal petroleum refining residues and similar carbonaceous material used in the manufacture of smokeless fuel by low temperature carbonization and for the driving off of hydrocarbon vapours therefrom, but it is not exclusively and solely applicable to the low temperature carbonization of coal as the apparatus is equally applicable to the mixing or agitation and simultaneous conveyance of tacky or pasty or solid materials generally as hereinafter mentioned.

Various substances that are solid under normal conditions become so tacky or viscous while undergoing heat treatment and adhere so firmly to the apparatus employed in treating them and set so hard on cooling that the apparatus soon becomes so coated, clogged and otherwise obstructed as to be rendered unworkable. The chief object of the present invention is to provide apparatus for enabling substances of the kind above stated to undergo heat treatment without rendering the apparatus inoperative.

The invention is however applicable to the agitation and simultaneous conveyance of materials for thoroughly mixing two or more components or drying or cooling or simultaneous heating and drying or heating and cooling various substances such for example as wood pulp.

With the above object in view and such others as are incidental thereto or hereinafter appear the invention in its broad aspect may be regarded as consisting in a chamber or casing and impellers therein which while impelling the material through the chamber are continually cleaning one another.

By regulating the feed of the material into the chamber in which it undergoes the treatment and by continually moving it onwards through the chamber an accumulation of an unwieldy mass is avoided, and by so shap-

ing and spacing the impellers that they are continually scraping or cleaning one another and the walls of the chamber, no firm adherence of the material either in pasty or solid form to the said impellers or chamber walls can take place.

In one simple form of the apparatus the impellers operate paddle-wise their paths of movement being overlapping circles and their distance apart being such that the tip of each impeller sweeps over the surface of a correspondingly shaped portion of an adjacent impeller during part of its travel. The chamber is preferably so formed that each impeller sweeps closely over a portion or portions of its wall during other portions of its travel.

The impellers may be arranged on a row of parallel shafts extending transversely across the chamber, into one end of which the material is fed from a chute and feed regulator.

According to one constructional form of the impellers each of them is rectangular in face view and multiple concave in end view or cross section. Each impeller may for example have two, three or four concave faces and be correspondingly rotated in two, three or four stages of angular movement per revolution and become temporarily locked in position after each stage of movement while the other impeller or impellers turn through one stage.

The above and other novel features will now be described more fully with reference to the accompanying drawings which are illustrative of various possible embodiments within the scope of the invention.

Figure 1 is a longitudinal sectional elevation of multiple impeller apparatus in accordance with the invention,

Figure 2 is a corresponding plan view,

Figure 3 is an end view in illustration of driving and locking mechanism for the impellers.

Figure 4 is a group of diagrams (a) to (e) illustrating the principle of operation of the apparatus.

Figure 5 is a longitudinal sectional eleva-

tion showing somewhat diagrammatically a modified form of apparatus.

Figure 6 is a fragmentary sectional elevation of the delivery end of the apparatus and means for removing the treated material therefrom.

Figure 7 is a fragmentary sectional elevation of special means for maintaining a gas passage along the upper part of the apparatus.

Figure 8 is a diagrammatic view of a further embodiment of the apparatus.

Figures 9 and 10 are diagrammatic views in plan and elevation of a further embodiment.

Referring first to the apparatus shown by way of example in Figures 1 to 5 it is to be observed that the apparatus comprises four impellers A, B, C, D, arranged side by side on parallel horizontal shafts projecting from their assembled casings which constitute the continuous chamber 1 in which the impellers turn. Each impeller is in the form of a drum having four concave faces and the impeller shafts are so spaced that the impeller paths overlap as shown. Impellers A and C are turned through a quarter revolution while B and D are locked stationary and then B and D turn in the same direction while A and C are locked stationary and so on. The tip of each moving impeller sweeps out the concavity presented by the adjacent face of the adjacent stationary impeller.

The material to be treated enters past a regulator 2 in a chute or hopper 3. In Figure 1 it passes along the top spaces of the impellers to the end one and thence down and along the bottom spaces to the outlet 4 (Figure 1). In Figure 5 on the other hand the material enters at one end of the chamber and passes out at the other end.

The operation of both types of apparatus above described will be readily understood by a consideration of Figure 4 in relation to Figure 5.

In Figure 4 stage (a) it is assumed that impellers A and C have performed 4 quarter-revolutions and that B and D are in the act of performing their fourth quarter-revolution while A and C are stationary. As will be seen and readily understood impeller B is clearing the material from the adjacent face of impeller A and eventually together with impeller D comes to rest in the position shown in stage (b).

Impellers A and C now perform another quarter-revolution and come to rest as shown at stage (c).

Impellers B and D then perform another quarter-turn and come to rest as shown at stage (d).

Impellers A and C then again perform another quarter-turn and come to rest as shown at stage (e), and so on.

From the foregoing and the accompany-

ing Figure 4 it will be seen that each impeller scrapes material from the preceding one and eventually presents it to the succeeding one. The material is thus conveyed along by impellers which constantly clean each other and also clean the walls of the chamber.

Any gases that may be evolved or any gases that may be introduced as a gaseous medium can escape through the gas passage 5.

If the material after treatment is not too sticky it will fall from the last impeller through the outlet 4 (Figure 5) and may be received into a tank 6 or one or other of two alternative tanks of water or other liquid which acts also as a gas-seal. If the material is liable to stick to the last impeller means may be provided to positively remove the same. An example of such means is shown in Figure 6, in which 7 represents a plate which is reciprocated by any convenient means (such as a cam slot not shown) to move inwards and recede at the correct rate to preserve in turn against each face of the impeller A a wall which diverts the plastic mass into a delivery conduit 8 along which it is forced and may be treated as it escapes so as to assume any desired form such as briquettes.

Although in the preferred constructional form above described, the floor and roof of the chamber are composed of arcuate portions corresponding to the sweep of the impeller tips, the roof need not be so shaped but may be flat or arched to provide a clear space above the impellers' paths, nor indeed need the floor be thus shaped particularly in the case of treating material that is or becomes semi-plastic because even if the floor be uniformly flat such material will collect to some extent and be shaped by the sweep of the impellers to assume a multiple arcuate formation as shown in Figure 5. The arcuate-shaped roof for the multiple-impeller chamber is preferable in some respects but it does not present an easy path of travel for evolved gases, and I may therefore resort to the construction shown in Figure 7 to ensure this path.

This consists in forming gaps or slots 9 on the end edges of the impellers near their tips and providing stationary lugs or studs 10 or the like on the chamber end walls which register with the slots as the slotted portions of the impellers sweep past them. In this way the said slots or gaps which would normally become clogged by the solid material under treatment are automatically de-clogged by the lugs or studs. The most convenient position for the de-clogging lugs or studs is symmetrically in the space that is common to adjacent impellers as shown in Figure 7 so that they first serve to clear the slots on one impeller and become themselves loaded by the clogging mass and then themselves become cleared by the slots of the adjacent impeller. It will be understood that the lugs or studs 130

project inwardly from the end walls of the enclosing chamber, each lug or stud being substantially diamond shaped in end view but with arcuate edges instead of straight edges.

5 The impellers are not necessarily arranged as a single row on parallel horizontal axes as in Figures 1 and 5 but may be nested as for example by being arranged in a plurality of rows with intervening interconnecting impellers as for example in zig zag form as shown in Figure 8.

The impeller shafts are not necessarily horizontal and may in fact be vertical as will be understood by regarding Figures 4 and 8 for example as being plan views instead of elevations; in this case gravity will prevent the material from rising to the roof and a free space for gases will naturally be preserved over the top ends of the impellers, as 20 shown in Figure 10.

In Figures 9 and 10 the impellers shown have three arcuate faces in place of four, this construction being preferable with some materials as the cavities are deeper and the 25 scraping edges have a greater scooping effect and a less squeezing effect on the material than is the case with shallow cavities.

The intermittent movements of the impellers may be effected by any appropriate 30 means such for example as ratchet and pawl or rack and pinion mechanism the odd numbered impellers (A and C) being moved together while the even numbered impellers (B and D) are locked and vice versa, and 35 the driving of these two groups of impellers being alternating for the successive stages of movement. Driving mechanism of this kind is shown in Figure 3 where a driving shaft 11 operates through gears to drive a rotary 40 cam disc 12 which actuates a roller 12' common to two lever mechanisms adapted to rock locking pawls 13 and 14 against the counter-force of springs 13* and 14* into and out of engagement with quadrantly notched discs 45 15 and 16 on countershafts 17 and 18, while eccentrics 19 and 20 are operated from the same driving shaft to swing ratchet pawls 21 and 22 repeatedly through small angular feed movements, and thereby turn ratchet wheels 50 on the shafts 17 and 18 and hence also the shafts themselves angular distances cumulatively amounting to quarter revolutions between each locking stage, shaft 17 being locked while 18 is turned and vice versa. The 55 shafts 17 and 18 are geared at 17', 18' to the shafts of the impellers A C and B D respectively. As shown the locking pawls 13 and 14 are integral with rocking levers 13' and 14' respectively formed with curved tracks 13** and 60 14** adapted to engage rollers 21* and 22* on the tails of the pawls 21 and 22 which are pivotally carried on arms 21' and 22' on the shafts 17 and 18 respectively.

The connecting rods 19' and 20' respectively between the eccentrics 19 and 20 and

the pawl-carrying arms 21' and 22' respectively are resiliently telescopic by means of stiff springs which will yield and permit the eccentrics to continue to turn but without effect in the event of the impellers becoming jammed in their cylinders by obstructive material and thereby preventing the ratchet pawls 21 and 22 from turning the shafts 17 and 18.

The conditions to be observed in utilizing the apparatus will naturally differ for different substances. In the case for example of requiring to merely heat or dry or both heat and dry a damp or pasty or sticky mass the apparatus may be heated to a uniform 70 temperature or to temperature progressively increasing along its length and the heat may be applied externally as for example by gas jets as shown at 1^a in Figure 5 or for example by hot air or steam or other gases. 75 If the mass enters the apparatus in a hot condition and requires to be cooled, the apparatus may be kept cool in any desired manner as for example by a cold water jacket or by circulation of cold air or gases inside 80 the apparatus. In either of the above cases the impellers themselves may if desired be made hollow to accommodate a heating or cooling medium.

In the case of requiring to subject a material to some treatment regardless of temperature as for example the exposure of a mass to the action of a gaseous chemical reagent, the provision of heating or cooling means may be dispensed with.

In the case of mixing two or more substances with or without the application of heat, particularly the mixing of materials that become tacky or pasty during the mixing operation, provision may be made for the introduction 95 of the component materials at any suitable point or points along the apparatus.

In the case of heating material to evolve 100 gases or vapours therefrom I may utilize the evolved gases or vapours after superheating the same as the heating medium. For this purpose a fan may be employed to force the superheated gases or vapours through the interior of the chamber. To assist in the heating of the chamber the evolved gases or vapours after issuing therefrom may be conducted under or around the chamber before passing to condensers or the like for subsequent treatment. The length of the chamber and the speed of travel of the material through it are such that practically all or 105 as much of the gases and vapours as may be desired are extracted.

The impellers may be made of metal or concrete or other suitable material and their scraping tips may be metal-shod or otherwise renewable. Similarly the chamber may be of firebrick or other non-metallic material or it may be of metal and provided with liners.

125 The apparatus may be adapted for treat-

ment of materials under pressure greater than atmospheric or under reduced pressure or high vacuum, with or without simultaneous heating or cooling.

5. What I claim is:—

1. Agitating and conveying apparatus comprising a chamber, a plurality of concave-faced drums of polygonal cross section mounted rotatably within the chamber with their axes parallel and at a distance apart providing overlapping paths of rotary movement, and means for imparting a partial rotation to odd numbered drums while the even numbered are stationary and vice versa. 70

15. Agitating and conveying apparatus comprising a chamber, a plurality of concave-faced drums of polygonal cross section mounted rotatably within the chamber with their axes parallel and at a distance apart such that each drum during a partial rotation sweeps into the concavity of the adjacent face of an adjacent drum, and means for imparting a partial rotation to odd numbered drums while the even numbered are stationary and vice versa. 75

20. Agitating and conveying apparatus comprising a chamber, a plurality of concave-faced impeller drums of polygonal cross section mounted rotatably within the chamber with their axes parallel and so shaped and spaced that each drum during rotation sweeps into the concavity of the adjacent face of a preceding drum thereby scooping out material in the cavity and thereafter by further rotation presents it for being scooped by a succeeding drum, and means for rotating odd numbered drums while the even numbered are stationary and vice versa. 80

25. Agitating and conveying apparatus comprising a chamber, a plurality of concave-faced impeller drums of polygonal cross section rotatably mounted within the chamber with their axes parallel and so shaped and spaced that each drum during rotation scoops material under treatment from a preceding drum and presents it for being scooped by a succeeding drum, means for rotating odd numbered drums while the even numbered are stationary and vice versa, and means for locking each drum while the material on one face thereof is being removed by a succeeding drum. 85

30. Agitating and conveying apparatus comprising a chamber, a plurality of concave-faced impeller drums of polygonal cross section rotatably mounted within the chamber with their axes parallel and so shaped and spaced that each drum during rotation sweeps into the concavity of the adjacent face of an adjacent drum, means for rotating odd numbered drums while the even numbered are stationary and vice versa, and means for heating the material as it is being impelled. 90

35. Agitating and conveying apparatus

comprising a chamber with multiple inverted arched floor, a plurality of concave-faced drums of polygonal cross section mounted rotatably within the chamber with their axes parallel and at a distance apart providing overlapping paths of movement each corresponding with an arch of the floor and means for imparting a partial rotation to odd numbered drums while the even numbered are stationary and vice versa. 95

7. Agitating and conveying apparatus comprising a chamber with multiple arched roof and multiple inverted arched floor, and a plurality of concave-faced impeller drums of polygonal cross section mounted rotatably within the chamber with their axes parallel and so shaped and spaced that each drum during rotation sweeps closely over corresponding arched roof and floor portions and into the concavity of the adjacent face of a preceding drum thereby scooping out material in the cavity and thereafter by further rotation presents it for being scooped by a succeeding drum, and means for rotating odd numbered drums while the even numbered are stationary and vice versa. 100

8. Agitating and conveying apparatus comprising a chamber with multiple arched roof and multiple inverted arched floor, a plurality of concave-faced impeller drums of polygonal cross section mounted rotatably within the chamber with their axes parallel and so shaped and spaced that each drum during rotation sweeps closely over corresponding arched roof and floor portions and into the concavity of the adjacent face of a preceding drum thereby scooping out material in the cavity and thereafter by further rotation presents it for being scooped by a succeeding drum, means for rotating odd numbered drums while the even numbered are stationary and vice versa, and means for locking each drum while the material on one face thereof is being removed by a succeeding drum. 105

9. Agitating and conveying apparatus comprising a chamber with multiple arched roof and multiple inverted arched floor, a plurality of concave-faced impeller drums of polygonal cross section mounted rotatably within the chamber with their axes parallel and so shaped and spaced that each drum during rotation sweeps closely over corresponding arched roof and floor portions and into the concavity of the adjacent face of a preceding drum thereby scooping out material in the cavity and thereafter by further rotation presents it for being scooped by a succeeding drum, means for rotating odd numbered drums while the even numbered are stationary and vice versa, and projecting means on the wall of the chamber in registering position with respect to slots on the ends of the drums whereby said slots are automatically de-clogged by said means as 110

the drums rotate and thereby ensure a continuous gas passage along the chamber.

10. Agitating and conveying apparatus comprising a chamber with multiple arched 5 roof and multiple inverted arched floor, a plurality of concave-faced impeller drums of polygonal cross section mounted rotatably within the chamber with their axes parallel and so shaped and spaced that each drum during 10 rotation sweeps closely over corresponding arched roof and floor portions and into the concavity of the adjacent face of a preceding drum thereby scooping out material in the cavity and thereafter by further 15 rotation presents it for being scooped by a succeeding drum, means for rotating odd numbered drums while the even numbered are stationary and vice versa, and substantially diamond shaped studs projecting from the 20 end wall of the chamber each in a symmetrical position with respect to the overlapping paths of adjacent drums whereby said studs pass through the de-clog correspondingly located slots in the ends of the drums as they 25 rotate.

11. Agitating and conveying apparatus comprising a chamber, a plurality of concave-faced impeller drums of polygonal cross section mounted rotatably within the chamber with their axes parallel and so shaped and spaced that each drum during rotation sweeps into the concavity of the adjacent face of a preceding drum thereby scooping out material in the cavity and thereafter by 30 further rotation presents it for being scooped by a succeeding drum, means for rotating odd numbered drums while the even numbered are stationary and vice versa, means for locking each drum while the material on 35 one face thereof is being removed by a succeeding drum, and positive means for removing the material from the successive faces of the last impeller drum.

In testimony whereof, I have signed my 40 name to this specification.

MAXWELL McGUINNESS.
